UNITED STATES PATENT OFFICE

BERNARD S. FRANKLIN, OF NEW YORK, N. Y.

LIGHTER

Application filed January 25, 1929. Serial No. 334,879.

This invention relates to lighters, and more particularly to a method and means for fueling flint-spark lighters.

A popular type of pocket and table lighter, for smokers, is a lighter having a fuel reservoir, preferably containing absorbent material for holding benzine, gasoline, alcohol, or other volatile fuel, a wick projecting out of the reservoir, and a flint-spark mechanism for igniting the wick. Such a lighter is refueled by inverting it, removing a screw plug from its bottom, and transferring a quantity of fuel through the resulting opening by means of a medicine dropper or similar device. To lessen this difficulty special cans of fuel have been marketed, designed somewhat like an oil can, but these add greatly to the expense of the fuel, and are not nearly so commonly available as are the more usual fuels.

In copending joint applications of Jerome B. Stern and the present applicant, Serial Numbers 334,877, and 334,878, filed concurrently herewith, there are described self filling lighters arranged to suck fuel upwards from an open body of fuel by first reducing and thereafter increasing the effective internal volume of the lighter. A preliminary reduction in volume is needed to permit of the desired expansion for filling. A final reduction in volume is desirable to discharge excess fuel above saturation, but this must be followed by an expansion in order to restore the lighter to its normal volume.

One object of my invention is to eliminate the foregoing wasted movements, and to provide a method for saturating the absorbent fuel holding material in a lighter, and to discharge any excess fuel, with only two movements. My method includes connecting the lighter with an open body of the fuel, expanding the effective internal volume of the lighter above its normal volume in order to suck fuel into contact with the absorbent material, and restoring the initial volume of the lighter to discharge excess fuel. If necessary the foregoing operation may be repeated until the absorbent material is fully saturated, the final contraction to the initial and normal volume serving to discharge the excess fuel.

A further object of my invention is to provide a simple and inconspicuous pumping means having a maximum displacement for a minimum of space, and to this end I provide a cylinder occupying and, in fact, constituting one entire side of the lighter. The cylinder is in communication with the fuel reservoir and a piston is reciprocated in the cylinder in order to pump fuel into the reservoir. The cylinder and piston may be arranged to first reduce, and thereafter restore, the volume of the lighter, and thereby suck fuel into the lighter, but I consider it preferable, for reasons already suggested, to first increase and thereafter restore the initial volume of the lighter, thereby insuring that any excess of fuel above saturation is discharged.

As is described in the joint applications already referred to, in order to connect the lighter with a body of fuel a suction pipe is provided, and to permit this to be placed out of the way when not in use it is pivoted to the lighter body and provided with resilient means for causing it to position itself either substantially parallel to the lighter, or substantially perpendicular thereto. To prevent free evaporation of the fuel, means are provided for closing an end of the pipe when it is in the parallel position. To prevent fuel from entering the pump cylinder, the points of connection of the cylinder and of the suction pipe with the reservoir are placed so far apart that fuel does not rise in the reservoir to a level sufficiently high to enter the cylinder.

My invention is further described in the following specification, which is accompanied by drawings in which Figure 1 is a partially sectioned elevation through one form of lighter embodying my invention; Figure 2 is a partially sectioned elevation through a preferred modification; and Figures 3 and 4 are details of the arrangement shown in Figure 2.

Referring to Figure 1 it will be seen that there is a lighter having a conventional sparking mechanism, but which is provided with a cylinder 2, forming one of the rounded sides of the lighter body, and a slightly recessed bottom 4, concealing a suction pipe 6.

The pipe is fixed to a square member 8, against which bears a resilient spring 10, thereby positioning the suction pipe 6 either substantially parallel to the lighter body, 5 and against a seat 12, to prevent evaporation, or substantially perpendicular to the lighter body, when it is to be used. The square member 8 is threaded to a pipe elbow 14, the thread therebetween permitting the necessary rotational movement of the suction 10 pipe 6.

The cylinder 2 carries a piston made up of several laminations of yieldable material 20, supported between washers 22, clamped together by the nuts 24. The piston is actuated, through a piston rod 26, by a knob 28, the rod 26 being guided by and closely fitting a bushing 30.

There is a passage 32 between the cylinder 20 and the fuel reservoir, and an opening 34 leading to free atmosphere.

To fill the lighter it is merely necessary to drop the suction pipe 6, raise the handle 28, immerse the pipe in fuel, and depress the 25 handle. The resulting suction draws a quantity of fuel into the fuel reservoir, where it contacts with and saturates the absorbent material 80.

A copending application of Albert M. 30 Franklin, Serial Number 334,880, filed concurrently herewith, discloses the idea of dispensing with a separate suction pipe by making the wick cap arm act also as a suction pipe. Such a modification is shown in Figure 2, in which the wick cap arm 50 is tubular, and is fixed to a square member 52, which engages a resilient spring 54, and is threaded to a pipe elbow 56, in communication with the fuel reservoir. These connections are 35 shown in greater detail in Figure 3, a fragmentary plan view, and Figure 4, a fragmentary sectional elevation, which are self explanatory, like reference numerals being applicable.

45 In the arrangement shown in Figure 2 a slightly different pump action has been shown, embodying a further feature of my invention. In this case communication with the reservoir is made from the closed end of 50 the cylinder, that is, the end of the cylinder away from the piston rod, and the resulting point of communication is separated from the point of connection of the suction pipe 55 with the fuel reservoir, in order to prevent fuel from entering the cylinder, by means of a pipe 60. This has been shown as situated on the center line of the lighter, in order to simplify the drawing, but actually will be fitted in one of the recesses formed by 60 the junction of the sides of the lighter with the cylinder 2.

The piston rod is loosely riveted at 66 to permit rotation of a knurled screw plug 62, threaded into the cylinder 2. The piston stop 65 and piston rod guide 64 is in this case given a

very loose fit, for atmospheric access. The piston itself is like that shown in Figure 1 except that one washer, 68, is threaded and replaces one of the nuts 24.

In operation it is merely necessary to lift 70 the wick cap arm 50, invert the lighter, immerse the end of the wick cap arm in the fuel, unscrew or release the handle 62, and then raise the handle and piston. This draws fuel directly into the fuel reservoir, and into 75 contact with the absorbent material 80. After a slight delay the piston may be lowered, discharging excess fuel, and the operation ordinarily is complete, owing to the large displacement of the pump. However, 80 if no excess fuel is discharged the operation may be repeated until full saturation is obtained.

The pump mechanism shown in Figure 2 has the advantages of not requiring a tight 85 seal between the piston rod and its bushing, and of permitting greater total displacement. Either pump system may be employed with either form of lighter shown.

In either lighter the customary manual 90 filling plug 16 is provided, in order to permit the wick and absorbent material to be inserted in the lighter, and to carry spare flints.

I prefer to dispense with suction and discharge valves, even though they would make it possible to use a very small cylinder, because with present lighters it is not desirable to have free liquid in the fuel reservoir, owing to leaks. In the present scheme the 100 absorptive property of the absorbent material gives the desired valve action, mere saturation being desired, for the operation may be repeated, if necessary, until full saturation is reached, and excess fuel is discharged. 105

I claim:

1. The combination with a lighter of a suction pipe of substantial length movably attached thereto so that it may be moved between an operative position projecting from the reservoir and an inoperative position not projecting from the reservoir for connecting the lighter with an open body of the fuel, and means to expand the effective internal volume of the lighter above its normal value in order to suck fuel through the pipe into the lighter. 110

2. The combination with a lighter containing absorbent fuel holding material of a suction pipe of substantial length pivotally attached to the lighter for connecting the lighter with an open body of the fuel, and means either to expand the effective internal volume of the lighter above its normal value in order to suck fuel through the pipe into contact with the absorbent material to saturate it or to restore the initial volume to discharge any excess fuel. 120

3. A lighter having a fuel reservoir, a 130

5 pump comprising a relatively movable cylinder and piston for pumping fuel upwards into the lighter, manually operable means for actuating the pump, and means to prevent fuel from entering the pump.

10 4. A lighter comprising a fuel reservoir, a cylinder in communication therewith, a reciprocable piston in the cylinder, means to reciprocate the piston in order to pump fuel into the reservoir, and means to prevent fuel from entering the cylinder.

15 5. A lighter comprising a fuel reservoir, a suction pipe connected thereto, a cylinder also in communication therewith, a reciprocable piston in the cylinder, and means to reciprocate the piston in order to increase the effective internal volume of the reservoir to suck fuel through the pipe into the reservoir, the points of connection of the cylinder 20 and of the pipe with the reservoir being so spaced that fuel does not enter the cylinder.

25 6. A lighter comprising a fuel reservoir, a suction pipe pivoted thereto and in communication therewith, resilient means for causing said pipe to position itself either substantially parallel to the lighter or substantially perpendicular thereto, means for closing an end of the pipe when it is in the parallel position, a cylinder in communication with 30 the fuel reservoir, a reciprocable piston in the cylinder, and means to reciprocate the piston in order to increase the effective internal volume of the reservoir to suck fuel through the pipe into the reservoir.

35 7. A lighter comprising a fuel reservoir containing absorbent fuel holding material, a suction pipe connected thereto, a cylinder also in communication therewith, a reciprocable piston in the cylinder, and means to reciprocate the piston in order to increase the effective internal volume of the reservoir to suck fuel through the pipe into contact with the absorbent material to saturate it, the 40 points of connection of the cylinder and of the pipe with the reservoir being so spaced that fuel does not enter the cylinder.

BERNARD S. FRANKLIN.
